UNITED STATES PATENT OFFICE.

GUSTAV BERNHARD PETSCHE, OF PHILADELPHIA, PENNSYLVANIA,
ASSIGNOR TO THE SOUTHWARK FOUNDRY & MACHINE COMPANY,
OF PHILADELPHIA, PENNSYLVANIA, A CORPORATION OF
PENNSYLVANIA.

VALVE-ACTUATING MECHANISM FOR BLOWING-ENGINES.

SPECIFICATION forming part of Letters Patent No. 758,931, dated May 3, 1904.

Application filed February 2, 1900. Serial No. 3,692. (No model.)

To all whom it may concern:

Be it known that I, GUSTAV BERNHARD PETSCHE, a subject of the Emperor of Germany, residing in the city and county of Philadelphia, in the State of Pennsylvania, have invented a certain new and useful Improvement in Valve-Actuating Mechanism for Blowing-Engines, of which the following is a true and exact description, reference being had to the accompanying drawings, which form a part thereof.

My invention relates to blowing-engines of the type having admission and delivery valves of the sliding-gridiron type in each head of the compressing-cylinder. In such engines the admission-valves are positively, though intermittently, actuated in a fixed relationship to the constantly-moving parts of the engine, and although for the best results the delivery-valve should be opened at varying periods, dependent on the compression of air in the receiver, it is also desirable that they should be closed by a positively-acting mechanism and, like the admission-valves, in a fixed relation to the constantly-moving parts. The intermittently-acting mechanism for opening and closing the admission-valves and for closing the delivery-valves is most conveniently made to embody cams both because they are well adapted for giving intermittent motion to connect the ports and because the character of the motion imparted can be most conveniently regulated by means of cams.

The object of my invention is to provide a simple and highly-efficient actuating device for actuating the valve-actuating mechanism aforesaid and a device particularly which simplifies the independent adjustment of the individual valve-actuating mechanisms; and, generally speaking, my invention consists in securing in a plane intermediate of the heads of the compressing-cylinder a rock-shaft actuated, preferably, through adjustable connections by a positively-moving part of the engine and connecting said rock-shaft inde-

pendently with each of the individual valve-actuating cam mechanisms preferably also by adjustable connections. For the best results the connection between the intermediate rock-shaft and the valve-actuating devices should be of such a character that an adjustment in the connection of the intermediate shaft with its actuating devices will similarly change the adjustments of all the parts, while of course each individual connection from the intermediate shaft can be adjusted without making any change in the adjustment and relative motion of the other connections.

Reference being now had to the drawings, in which my invention is illustrated, Figure 1 is a side elevation of a blowing-engine provided with my improved valve-actuating mechanism. Fig. 2 is a front view of the compressing-cylinder and valve-actuating devices. Fig. 3 is a cross-section taken on the line 3 3 of Fig. 6. Fig. 4 is an enlarged detail of Fig. 3. Fig. 5 is a vertical section taken on the line 5 5 of Fig. 6, and Fig. 6 is a plan view taken on the section-line 6 6 of Fig. 5.

A indicates the framing of the engine; B, the steam-cylinder, having a steam-admission pipe B' leading to it and an exhaust-pipe B² leading from it.

C is the compressing-cylinder, having an upper head C' and lower head C².

C³ indicates the ports of the delivery-valve through the upper head, and C⁴ the similar ports in the lower head.

C⁵ indicates the admission-ports in the upper head; C⁶, the similar ports in the lower head.

C⁷ indicates the receiver at the top of the cylinder; C⁸, the receiver at the bottom of the cylinder, said receivers connecting, through a pipe C⁹, with a common blast-pipe C¹⁰.

D is the piston-rod connecting the compressing-piston D' with the piston (not shown) in the steam-cylinder. This piston-rod has secured to it trunnion-like bearings, (indicated

at D'), on which are pivoted connecting-rods, as indicated at E, coupled to cranks E', secured on the main shaft E² of the engine.

E³ indicates an eccentric on the main shaft, 5 on which is secured an eccentric-strap E', having an arm e⁴, coupled to a bell-crank lever E⁵, which lever is also coupled to a connecting-rod E⁶, having in it an adjusting device, as indicated at e⁶, and coupled at top to a lever- 10 arm E⁷, secured to a rock-shaft F, having its bearings in arms G G, secured to the cylinder C between its upper and lower heads.

F' and F² are oppositely-extending lever-arms secured to the shaft F and connected, as 15 will be described, with the mechanism for closing the delivery-valves of the engine. f' f² are similar oppositely-extending lever-arms of the shaft F, coupled with the mechanism for moving the admission-valves of the engine.

20 H and h are respectively the upper and lower delivery-valves of the compressing-cylinder, best placed, as shown, so as to face toward the cylinder with their backs exposed to the pressure of the air in the receivers.

25 The actuating mechanisms for the valves being similar, that for the upper valve being lettered with capitals and that for the lower valve with small letters, it will be sufficient to describe only the upper-valve-actuating mechanism.

30 The rod H' of the valve H passes through the stuffing-box into a cylinder I and is secured to a piston H², moving in said cylinder and preferably formed with an open-ended cylindrical opening H³ in its rear face, as shown in 35 Figs. 3 and 4.

H⁴ is a cylindrical projection extending in from the head of the cylinder H³.

K is a conduit connecting the front end of 40 the cylinder I with the interior of the compressing-cylinder C at a point near the end of the cylinder, but sufficiently far from it to be uncovered by the piston D² after it has passed over it and is at the top of its stroke. In the conduit K, I provide at K' valve mechanism which permits the free entrance of air from the cylinder C into the cylinder I. It regulates the back flow of or from the cylinder I into the cylinder C. This may be of any convenient character.

45 It will readily be understood that as the piston D² moves upward the air compressed in front of it passes through the conduit K into the cylinder I and acts against the face of the piston H², tending to move the valve H in a direction to open with an increasing force, which is resisted by the weight of the valve and by the constantly-diminishing excess of pressure holding the valve to its seat. In practice these forces tending to hold the valve 55 closed are sufficient to overcome the pressure on the actuating-piston until the pressures in the compressing-cylinder and the receiver are substantially equal, when the valve is opened 60

with great rapidity. It will also be obvious that after the compressing-piston has passed 65 above the conduit K the air in the cylinder I is free to flow back into the cylinder C with such rapidity as may be determined by the regulating device K'.

Secured to the rear of the cylinder I are 70 guideways (indicated at I') which support a slide J, having a recessed portion J', provided at front and rear, as indicated, with cam-rollers J² and J³. In the devices shown the slide J has secured to its front end a piston J⁴, which 75 moves in the cylinder H³ of the piston H² and is preferably formed with a central cylindrical opening J⁶ and a regulable air-escape, (indicated at J⁵). It will readily be understood that as the piston H² moves backward its cylindrical 80 portion will move over the piston J⁴, the air escaping freely through the opening J⁶ until the piston, like cylinder H⁴, enters the cylindrical opening J⁶, after which the air is compressed in the cylinder H³ and permitted to 85 escape only with determined rapidity through the regulable device J⁵. The function performed by this device is to cushion the movement of the valve and its connected parts in 90 opening—a function which is performed irrespective of the position of the slide J, which is actuated by intermittently-moving mechanism, and its forward stroke has the duty of closing the delivery-valve. This particular device forms the subject-matter of a separate 95 application for a patent filed January 22, 1900, Serial No. 2,309.

L is a rock-shaft passing through the recess J' of the slide J and having secured to it a cam L', which rests in contact with the cam-rollers J² and J³. L² is a lever-arm, also secured to the shaft L and actuated by the rod M, having an adjusting device M', with the lever-arm F² of the intermediate rock-shaft F. The oppositely-extending lever-arm F² is 105 similarly connected by the rod m, having the adjusting device m', with the cam-actuating lever l', which is connected to the shaft l similarly to the arm L², the cams L' and l', however, being adjusted, as shown, so that in 110 each movement of the rock-shaft F one moves to close its controlled delivery-valve and the other moves away to permit the opening of its controlled delivery-valve.

Referring next to the admission-valves, 115 which are indicated at N n and which are preferably placed so as to face outward from the compressing-cylinder, the upper and lower valves and their connections being similarly lettered except that the upper one is indicated by capitals and the lower one by small letters, it will be again sufficient to describe the upper-valve connections.

N' indicates the valve-rod, which passes through the end of the cylinder C and is 120 coupled to a slide O, recessed, as indicated at

O', and provided with cam-rollers O² and O³, said slide moving in a guideway, (indicated at P.)

- Q indicates a rock-shaft extending through 5 the recess O' and having secured to it a cam Q', the surfaces of which are in contact with the cam-rollers O² and O³, and which cam and the shaft Q are actuated by a lever-arm Q², connected by a rod R, having an adjusting device 10 R' with the lever-arm f² of the shaft F, the similar connecting-rod for the lower admission-valve being indicated at r and coupled with the oppositely-extending lever-arm f'.

It will be obvious that for each movement 15 of the rock-shaft F the admission-valves at opposite ends of the compressing-cylinder are actuated in different directions, the one closing and the other opening. It will also be obvious that in the arrangement shown and 20 described an adjustment of the rod E⁶, as by means of its adjusting device e⁶, will similarly shift the position of all the valve-actuating devices connected with the rock-shaft F, while each one of these actuating devices can be ad- 25 justed independently of the other and without requiring any adjustment in the connection E⁶.

Having now described my invention, what I claim as new, and desire to secure by Letters Patent, is—

- 30 1. In a blowing-engine having admission and delivery valves of the sliding-gridiron type at both ends of the compressing-cylinder and all moving in planes parallel to each other and transverse to the axis of the cylinder, the combination of oscillating cams arranged to move the admission-valves in both directions and in a positive relation to the moving parts of the engine, another set of oscillating cams arranged to move the delivery-valves in the 35 direction to close them but not to open said valves, resilient, intermittently-acting means acting to open the delivery-valves, a rock-shaft situated in a plane lying between the ends 40 of the cylinder and running transversely to the lines of movement of the valves, oppositely-extending lever-arms f², f', secured to the rock-shaft, rods R, r, connecting said lever-arms with the cams of the admission-valves, another set of oppositely-extending lever-arms F², F', secured to the rock-shaft, rods M, m, connect- 45 ing said arms with the cams of the delivery-valves, and means for communicating motion to the rock-shaft from a positively-moving part of the engine.

of the cylinder and running transversely to the lines of movement of the valves, oppositely-extending lever-arms f², f', secured to the rock-shaft, rods R, r, connecting said lever-arms with the cams of the admission-valves, another set of oppositely-extending lever-arms F², F', secured to the rock-shaft, rods M, m, connect- 50 ing said arms with the cams of the delivery-valves, and means for communicating motion to the rock-shaft from a positively-moving part of the engine.

2. In a blowing-engine having admission and delivery valves of the sliding-gridiron type at both ends of the compressing-cylinder and all moving in planes parallel to each other and transverse to the axis of the cylinder, the combination of oscillating cams arranged to move the admission-valves in both directions and in a positive relation to the moving parts of the engine, another set of oscillating cams arranged to move the delivery-valves in the direction to close them but not to open said 60 valves, resilient, intermittently-acting means acting to open the delivery-valves, a rock-shaft situated on a plane lying between the ends of the cylinder and running transversely to the lines of movement of the valves, oppositely-extending lever-arms f², f', secured to the rock-shaft, rods R, r, connecting said lever-arms with the cams of the admission-valves, another set of oppositely-extending lever-arms F², F', secured to the rock-shaft, rods M, m, connect- 65 ing said arms with the cams of the delivery-valves, means for independently adjusting the length of each of the rods R, r, and M, m, and means for communicating motion to the rock-shaft from a positively-moving part of the 70 engine, said means embodying an adjustable rod, such as E⁶.
